UNITED STATES PATENT OFFICE.

CHARLES M. PECK, OF NEW HAVEN, CONNECTICUT,

DESIGN FOR A BRACKET.

SPECIFICATION forming part of Design No. 20,172, dated September 30, 1890.

Application filed August 16, 1890. Serial No. 362,225. Term of patent 7 years.

To all whom it may concern:

Be it known that I, CHARLES M. PECK, a citizen of the United States, residing at New Haven, in the county of New Haven and State 5 of Connecticut, have invented and produced a new and original Design for Brackets, of which the following is a specification, reference being had to the accompanying drawing, forming a part thereof.

10 My invention relates to a novel design for brackets; and it consists in the arrangement and forms of the parts thereof.

The accompanying drawing is a side elevation of my bracket.

15 The leading feature of my design consists in a curved brace extending from near the front end of the shelf-rest to a point near the lower end of the back, the arch located near the center of the curved brace with its convex

20 side projecting upwardly, the arch located near the juncture of the shelf-rest and back with its convex side projecting downwardly;

and a post extending from one arch to the other. The shelf-rest A and back B are supported by the angular brace G and curved 25 brace C, to which is connected the arch D. From the crown of the arch D extends the post F, which is joined to the crown of the arch E, the ends of which are secured to the shelf-rest A and wall-piece B. 30

What I claim is—

The herein-described design for a bracket, the same consisting of the shelf-rest A, back B, and brace C, and the ornamentation of the same, consisting of two arches, the convex 35 sides of which are presented toward each other, and a straight connection between the arches at their centers, substantially as shown in the accompanying drawing.

CHARLES M. PECK.
